CLAIM

The ornamental design for a young child vehicle, as shown and described.

DESCRIPTION

The nature and intended use of the article in which the design is embodied is that of a small vehicle for children and the like. FIG. 1 is a perspective view of a young child vehicle showing my new design;

FIG. 2 is a rear view thereof;

FIG. 3 is a front view thereof;

FIG. 4 is a side view thereof; and,

FIG. 5 is a top view thereof.
